UNITED STATES PATENT OFFICE.

ALONZO N. EDMONDS, OF CHARLESTON, SOUTH CAROLINA.

RADIO RECEIVING APPARATUS.

1,306,474.

Specification of Letters Patent. Patented June 10, 1919.

Application filed October 2, 1915. Serial No. 53,737.

To all whom it may concern:

Be it known that I, ALONZO N. EDMONDS, a citizen of the United States, residing at Charleston, in the county of Charleston and State of South Carolina, have invented certain new and useful Improvements in Radio Receiving Apparatus, of which the following is a specification.

My invention relates to new and useful improvements in apparatus for transmitting intelligence by radiant energy, and has for its primary object the provision of a device of this character whereby a plurality of messages of different wave lengths may be received at one station, and means are also provided whereby the operators receiving the messages may verify their messages by "listening in".

Another object of the invention is to provide a device of the character above described having a plurality of antennae connected with a plurality of receiving circuits, means being associated therewith whereby the plurality of antennae may be utilized for sending a message.

A further object of the invention is to provide a circuit controlling means whereby the receiving instruments may be quickly and surely connected to the various receiving circuits, the receivers being connected in series when one message is received in both sets.

With the above and other objects in view my invention resides preferably in the construction, combination and arrangement of parts as hereinafter set forth in the specification and illustrated in the accompanying drawings, in which,

The figure is a diagrammatic view of the receiving system of a radio station.

Similar reference characters designate similar parts throughout the various views of the drawings.

In the drawing, I have illustrated my improved system for receiving messages by radiant energy which includes a plurality of antennae A and B, the antenna A having a conductor 1 leading therefrom to the primary winding 2 of the tuning coil T. The antenna B has a similar conductor 3 leading therefrom and communicating with the primary winding 4 of a second tuning coil T'. The conductors 5 and 6 communicate with the primary windings 2 and 4 and are grounded, as at 7 and 8, respectively. I provide what I term an anchor spark gap

which includes the transmitting conductor 9 having a terminal 10 disposed between the terminals 11 and 12. By the use of the conductor 9 in transmitting a message both of the antennae may be utilized. The tuning coils T and T' are provided with the usual secondary windings 13 and 14, respectively, said windings 13 and 14 having the receiving circuits *a* and *b*, respectively, extending therefrom. The circuits *a* and *b* include conductors 15, 16, 17 and 18, said conductors embracing, respectively, receivers 19 and 20, and the switch arms 21 and 22 of the isolating switch S. The usual condensers *c* and *c'* may be provided and shunted across the circuits *a* and *b*, respectively. Suitable detectors 23 and 24 may be interposed in the conductors 15 and 18, respectively, and the adjustable condensers 25 and 26 may be shunted across said circuits *a* and *b*, respectively. The switch S is provided with a plurality of intermediate contact points 27 and 28, respectively, said contact points communicating with the conductors 15 and 18, respectively, by means of the jumpers 29 and 30. A shunting switch 31 is disposed between the conductors 16 and 17 for a purpose which will hereinafter appear.

In order to permit listening-in on either of the receiving circuits *a* or *b* I provide listening-in circuits *x* and *y* and a receiver 32. A two-pole double-throw switch 33 serves to connect the receiver to one or the other of the listening-in circuits.

In operation, I will assume that there are two messages being sent from distant stations and it is desired that such messages be received in their entirety at the station represented by the diagrams in the drawings. To receive a plurality of messages the switch S is allowed to remain in the position shown in the figure, the switch 31 being maintained in the open position, as shown in this figure. The tuning coils T and T' are now adjusted to receive messages on the antennae A and B, it being of course assumed that the messages being received are of different wave lengths, the usual adjustments may be made in the detectors 23 and 24 and the condensers 25 and 26, these circuits being controllable entirely independently of one another. If a third operator desires to listen-in on either of the messages being received he may do so by moving the arm of the switch 33 into connection with one or the other of the circuits *x* and *y*.

Assuming that it is desired to receive a message of distress or the like the switch S may be moved to the right. The switch 31 is moved to the closed position which places the receivers 19 and 20 in series. In this position the message sent will be received through the tuning coil T. To receive a message through the tuning coil T' independently of the tuning coil T the switch S is moved to the left. It will thus be seen that messages of different wave lengths may be simultaneously received by my improved system, or very important messages may be received and verified by the two receivers being connected in series. It will also be noted that when it is desired to send a message the anchor spark gap comprising the terminals 10, 11 and 12 is provided to allow the use of both antennæ which of course gives a wider area from which the message may be delivered.

From the above description taken in connection with the accompanying drawings it is thought that a clear and comprehensive understanding of the construction, operation and advantages of my invention may be

readily gathered, and while I have shown and described the same as embodying a specific structure I desire that it be understood that I may make such changes therein which do not depart from the spirit and scope of the invention as claimed.

Having fully described my invention what I claim as new is:—

Radio receiving apparatus, comprising a plurality of antennæ, a main circuit for each antenna including a condenser, a receiver and a detector, switch means in the main circuits to admit of the receivers being used independently or in series with either of the circuits, and a listening-in circuit including portions connected with the main circuits and a portion containing a receiver and a switch to admit of the listening-in receiver operating with either main circuit or being rendered inactive.

In testimony whereof I affix my signature in presence of two witnesses:

ALONZO N. EDMONDS.

Witnesses:
